UNITED STATES PATENT OFFICE.

WOLFGANG TURNWALD, OF SYRACUSE, NEW YORK, ASSIGNOR TO STUMPF UNA-FLOW ENGINE COMPANY, A CORPORATION OF NEW YORK.

VALVE.

1,332,582.

Specification of Letters Patent.

Patented Mar. 2, 1920.

Application filed March 10, 1917. Serial No. 153,859.

To all whom it may concern:

Be it known that I, WOLFGANG TURNWALD, a subject of the Emperor of Austria, residing at Syracuse, in the county of Onondaga, State of New York, have invented a new and useful Improvement in Valves, of which the following is a specification.

My invention relates to improvements in valves. The object is to provide a valve 10 having a safety element adapted to give a greater opening with normal lift of the valve mechanism.

The invention comprises two elements, each having a face coöperating with a fixed 15 seat and each having a face coöperating with a face of the other, and means whereby the elements are actuated to separate from the said seats and from each other.

The invention also comprises improvements in arrangement and construction.

Referring to the drawings, which illustrate merely by way of example suitable means for the embodiment of my invention:

25 Figure 1 is a vertical section of a triple beat puppet valve embodying my improvement.

Fig. 2 is a fragmentary sectional view showing the upper element 7 in open position.

Fig. 3 is a vertical section showing modifications.

Fig. 4 is a fragmentary sectional view showing all the elements in the open position.

35 Fig. 5 is a sectional plan view of the device shown in Fig. 3; the section taken on line 5, 5 of Fig. 6.

Fig. 6 is a vertical cross-section on line 6, 6 of Fig. 5.

40 Fig. 7 is a fragmentary view in section showing faces 12 and 13 separated while faces 10 and 11 are in contact with each other.

Similar numerals refer to similar parts 45 throughout the several views.

Referring to Fig. 1, the valve comprises the two elements 6 and 7. Element 6 comprises a formation having a contact face 8 at its lower edge coöperating with the stationary valve seat 9, and a contact face 10 at its upper edge, coöperating with and forming a valve seat for the contact face 11

of element 7. Element 7 is also provided with a contact face 12 coöperating with the stationary valve seat 13. The contact faces 11 and 12 of element 7, are formed on the undersides of annular formations connected by the web 14. This web is preferably resilient. Element 7 is also provided with a collar or sleeve 15, which surrounds and 60 has a slight sliding movement on the sleeve 16, which is integral with element 6. Sleeve 16 is provided with the shoulder or enlargement, as at 17, adapted to engage, upon its upward movement, with the underside of sleeve 15. Sleeve 16 is adapted to receive the valve spindle 18, having the head 19 at its lower end. Above the sleeve 16 is provided the housing 20 also fitted on the spindle 18. Within this housing 20 is provided the spring 21 adapted to engage the shoulder 22 of element 7. This housing 20 is held in position by means of the nut 22^a threaded on the spindle 18 and maintains the spring 21 under the desired tension. 70 This housing 20 and nut 22^a also serve to maintain the spindle 18 in fixed engagement with the sleeve 16.

When used as a steam valve for engine cylinders, it will be understood that the 80 spindle is operated in the usual way, as for example, by means of a cam, actuated in connection with the operation of the engine, to open and close said valve.

By the upward movement of spindle 18, 85 element 6 is raised, causing a separation of faces 8 and 9; and at the same time causing an upward movement of element 7 and a separation of faces 12 and 13.

When the valve is closed however, in case 90 of water in the cylinder, or a very high compression, due to the breaking of the vacuum in a condensing engine, the upper element 7 acts as a safety valve. That is to say, either faces 12 and 13 will separate due to 95 the resilience of web 14, or element 7 will compress the spring 21 and lift off the two seats 10 and 13 as in Fig. 2, and thereby prevent pressure in the cylinder from exceeding that of the boiler, except by a slight 100 amount due to the spring, the weight of the valve and the slight difference in areas.

Referring to Fig. 3, the element 6 is provided with a sleeve 23 having a vertical

movement on the stationary stud 24. Sleeve 23 engages at its upper end with the head 25 of spindle 18. This sleeve 23 is slotted, as at 26, to accommodate the levers 27, which are pivoted at 28 to the stationary post 29 projecting upwardly from stud 24. These levers 27 are provided with the elbows 30 which engage with the lower margins 31 of the slots 26 of sleeve 23.

10

Operation.

It will thus be seen that when the valve element 6 is lifted by means of spindle 18, the levers 27 will be actuated to force the element 7 upwardly a distance approximately twice that of the movement of element 6, as indicated in Fig. 4. That is to say, when the main valve 6 is lifted by the valve stem 18, the surfaces 31 of sleeve 23 actuate the levers 27. This causes the outer free ends of these levers, which engage the under side of element 7, to raise the flexible or safety valve element 7, higher than the main valve lifts. Upon such actuation we have a flow between faces 8 and 9, between 10 and 11 and between 12 and 13; or in other words, we have a triple beat valve in place of the usual double beat valve.

As the opening between 12 and 13 will be practically twice as much as the opening between 8 and 9, while the opening between 10 and 11 will be approximately the same as between 8 and 9, we really get about twice the opening in this valve, with the same size valve and the same lift of valve of the ordinary double beat type.

While the auxiliary or safety valve 7 lifts higher than the element 6, it requires no higher cam to lift it, and the valve being so light, the inertia force added to its extra lift is comparatively slight.

It will be obvious that the levers 27 form only one example of a number of means whereby the element 7 may be given a greater movement than the element 6. It will also be understood that by varying the proportions or dimensions of the levers the ratio may be increased or diminished.

What I claim is:—

- 50 1. A main valve element and a relatively movable auxiliary valve element, each having a face coöperating with a fixed seat and each having a face coöperating with a face of the other element, and means for causing a separation between the coöperating faces of said element, and a separation of the auxiliary element from its fixed seat greater than the separation of the main valve element from its fixed seat.
- 60 2. A main valve element and a relatively movable auxiliary valve element, each having a face coöperating with a fixed seat and each having a face coöperating with a face of the other element, and means for causing a separation of the face of the auxiliary ele-

ment from its fixed seat substantially greater than the separation of the face of the main element from its coöperating fixed seat.

3. A triple beat valve comprising two movable elements, each having a face coöperating with a fixed seat, and each having a face coöperating with a face of the other element, means for actuating one element, means for communicating movement of one element to the other, and resilient means adapted normally to hold the faces of one element in closed position when the valve is closed, but to permit movement of one or both of said faces upon occurrence of abnormal conditions.

4. A valve comprising two movable elements, each having a face coöperating with a fixed seat and each having a face coöperating with a face of the other, means for actuating one element and means whereby the said element actuates the other a distance substantially greater than that of its own movement.

5. A valve comprising two movable elements, each having a face coöperating with a fixed seat and each having a face coöperating with a face of the other, means for actuating one element and means for communicating the movement of said element to the other so that said elements will separate from their seats and from each other.

6. A valve comprising two movable elements, each having a face coöperating with a fixed seat and each having a face coöperating with a face of the other, means for actuating one element and a pivoted lever as means for communicating the movement of said element to the other so that said elements will separate from their seats and from each other.

7. A valve comprising two movable elements, each having a face coöperating with a fixed seat and each having a face coöperating with and separable from a face of the other, means for actuating one element and means for communicating the movement of said element to the other so that one element shall have a greater movement than the other and said elements shall separate from their seats and from each other.

8. A valve comprising two movable elements, each having a face coöperating with a fixed seat and each having a face coöperating with and separable from a face of the other, one of said elements having its two contacting faces in substantially the same plane.

9. A valve comprising two movable elements, each having a face coöperating with a fixed seat and each having a face coöperating with and separable from a face of the other, one of said elements having its two contacting faces concentric and in substantially the same plane.

10. A valve comprising two movable ele-

ments, each having a face coöperating with a fixed seat and each having a face coöperating with and separable from a face of the other, one of said elements having its two contacting faces resiliently connected.

11. A valve comprising two movable elements, each having a face coöperating with a

fixed seat and each having a face coöperating with and separable from a face of the other, one of said elements having its two ¹⁰ contacting faces resiliently connected and in substantially the same plane.

WOLFGANG TURNWALD.
